UNITED STATES PATENT OFFICE.

BENJAMIN ZETLIN, OF PROVIDENCE, RHODE ISLAND, ASSIGNOR TO A & Z CHAIN COMPANY, OF PROVIDENCE, RHODE ISLAND, A CORPORATION OF RHODE ISLAND.

BELT CLASP.

Application filed June 18, 1923. Serial No. 645,985.

To all whom it may concern:

Be it known that I, BENJAMIN ZETLIN, a citizen of the United States, residing at Providence, in the county of Providence and State of Rhode Island, have invented certain new and useful Improvements in Belt Clasps, of which the following is a specification.

My invention relates to loops or clasps adapted to embrace a belt and furnish support for the suspension chain of a watch, key ring, or other article.

The essential objects of my invention are security against accidental disengagement; facility of engagement with the belt, and of manual manipulation; and simplicity and inexpensiveness of construction.

To the above ends essentially my invention consists in such parts and in such combinations of parts as fall within the scope of the appended claim.

In the accompanying drawings which form a part of this specification,

Figure 1 is a front elevation of my novel device fixed to a belt and including a chain, Figure 2, a side elevation of the clasp showing the belt in section,

Figure 3, a section of the clasp in closed position taken on line 3—3 of Figure 1, and,

Figure 4, a like section of the same in closed position.

Like reference characters indicate like parts throughout the views.

In detail my novel clasp is formed from a thin strip of resilient metal, preferably of precious metal or plated with precious metal, and is bent therefrom into the desired form. It comprises a loop having legs 7 to 8 united by an intermediate bend 9. The leg 7, which

constitutes the rear portion of the loop, has a forwardly directed shoulder 11 terminating in a depending integral ring 12. Upon the upper face of the shoulder is a pointed projection 13. The lower end of the front leg has a rearwardly directed curved resilient lip 14 terminating in an upwardly directed portion 15. The lip is provided with a central opening or cavity 16. Engaged in the ring is one end of a chain 18 carrying on its end a swivel 19 adapted to receive a watch, ring, or the like.

The loop is applied to a belt 21 by pressing the former downwardly over the belt with the leg 7 in the rear thereof until the shoulder 11 is below the belt. The leg 8 is then manually pressed rearwardly whereby the lip portion 15 is caused to ride over the projection 13, and the lip to yield until the projection snaps into the cavity 16 in the position shown in Figure 3.

Obviously the width of the leg 8 may be varied and the contour thereof otherwise changed to enhance its ornamental appearance.

I claim:

A belt clasp comprising legs united by a terminal bend, a horizontal shoulder on one leg, a depending ring on the shoulder, a vertical projection on the shoulder, and a yielding lip on the other leg provided with an upturned terminal portion adapted to ride upon the projection, said lip being also provided with a cavity adapted to receive the projection.

In testimony whereof I have affixed my signature.

BENJAMIN ZETLIN.
